UNITED STATES PATENT OFFICE.

JOHN BEISWANGER, OF STEUBENVILLE, OHIO, ASSIGNOR TO GILL BROTHERS COMPANY, OF STEUBENVILLE, OHIO, A CORPORATION OF WEST VIRGINIA.

DESIGN FOR BEAN-POT AND COVER.

56,336.

Specification for Design.

Patented Oct. 5, 1920.

Application filed October 31, 1919. Serial No. 334,859. Term of patent 7 years.

To all whom it may concern:

Be it known that I, JOHN BEISWANGER, a citizen of the United States of America, and resident of Steubenville, county of Jefferson, State of Ohio, have invented a certain new, original, and ornamental Design for a Bean-Pot and Cover, of which the following is a specification.

In the accompanying drawing I have illustrated a bean pot and cover, constructed in accordance with my invention, the article being made of resistive transparent glass.

In the drawing Figure 1 is a perspective

taken from the side of a bean pot and cover showing my new design.

Fig. 2 is a top plan of the cover.

Having thus described and illustrated my invention, I claim:

The ornamental design for a bean pot and cover, substantially as shown.

Signed by me at Steubenville, Jefferson county, Ohio, this 22d day of October, 1919.

JOHN BEISWANGER.
